SPECIAL ORDER FORM

Jack Moss, Youngstown, Ohio

Application December 20, 1944, Serial No. 569,045

2 Claims. (Cl. 282—23)

1

This invention relates to order forms and more particularly to special order forms such as used by merchandising establishments, etc.

The principle object of the invention is the provision of a special order form incorporating a plurality of detachable sections which comprise the complete record of the special order.

A further object of the invention is the provision of a special order form, the formation of which provides means for placing a special merchandise order, establishing multiple records of the special order and provides a copy of the order for transmittal to the manufacturer and further provides the manufacturer with an address stub or reply card.

A still further object of the invention is the provision of a special order form incorporating a follow-up card to enable the establishment using the form to contact the manufacturer and request advice as to shipment of the goods in the event that shipment has been delayed beyond the usual time.

The special order form shown and described herein has been designed to expedite customer's special orders as handled by a retail merchandising establishment such as a department store, and provides on one form a copy and correlated record of the customer's special order, the handling of the order in the merchandising establishment and provides the manufacturer or shipper of the special order with an address stub or reply card if the shipping date is other than normal. At the same time the special order form provides an inquiry card which may be used by merchandising establishments placing the special order to inquire about the order and all of the various parts of which correspondingly numbered so that a uniform and accurate record may be kept.

With the foregoing and other objects in view which will appear as the description proceeds, the invention resides in the combination and arrangement of parts of the special order form hereinafter described and claimed, it being understood that changes in the precise embodiment of the invention herein disclosed can be made within the scope of what is claimed without departing from the spirit of the invention.

The invention is illustrated in the accompanying drawing, wherein the figure illustrates the special order form with various portions thereof partly detached and turned up to indicate the complete assembly thereof.

By referring to the drawing it will be observed that the special order form comprises essentially a top edge bound leaflet, the top or front cover

5 being indicated by the numeral 10 and the back or rear portion of the form being generally indicated by the numeral 11. The binding may be conventional gluing or stitching or stapling and is shown in the drawing as wire stitching and indicated by the numeral 12. Positioned between the front cover 10 and the back cover 11 of the special order form leaflet by means of the binding 12 there are two sheets, generally indicated by the numerals 13 and 14, which with the back cover 11 comprise the usable portions of the special order form, the front cover 10 carrying directions for use of the same on the inside cover thereof. The sheet 13 which is uppermost in the drawing is perforated on four lines, indicated by the numerals 15, 16, 17 and 18, respectively, so that it may be conveniently detached in appropriate portions. The uppermost portion of the sheet 13, indicated by the numeral 13A, comprises the portion of the form filled in by the sales person and carries such data as the customer's name, the address as well as the department and section in which the special order originates, and the name and number of the sales person, the kind of sale, the advanced payment, if any, and the receipt number, if any, as well as providing for the quantity, style, color, description, etc., concerning the specially ordered merchandise. Immediately beneath this portion 13A, on the back side thereof and indicated in the drawing by the numeral 13B, there is a provision made for a follow-up record and alphabetical customer file listing. These spaces can be filled in with various data concerning the special order if and when necessary. A one time carbon 19 separates this top section 13A of the top sheet 13 from the second sheet 14 and a correspondingly marked section 14A which in use comprises the department manager's copy. Another one time carbon 20 separates this second sheet 14 from the back cover for providing for a second copy of the portion 13A on the first sheet and comprises a special order date tickler which is filed in a date tickler file to be used by the merchandising establishment 45 in checking on the special order in view of the delivery date promised the customer.

By again referring to the uppermost or first sheet 13 it will be noted that the central section thereof comprises a detachable portion which is filled in by the department manager thereby completing the special order form. The middle portion is indicated by the numeral 13D and is detached. The bottom portion of the form is separated therefrom by the line of perforation 17, 50 and is generally indicated by the numeral 13F,

and is folded upwardly and the resulting post card shape is mailed to the manufacturer or shipper of the merchandise desired, it being observed that the opposite side of the portion 13D comprises a post card form with space for filling in the manufacturer's or shipper's name as indicated by the numeral 13E. These two portions 13D and 13F, when received by the manufacturer or shipper of the merchandise, may be employed for expediting the delivery of the special order to the retail establishment originating the same. This is possible by the formation of the lower portion 13F of the sheet 13 in the form of a combination address stub and business reply card. If the merchandise is to be shipped immediately, the bottom portion 13F is detached on the perforated line 17 and the same again separated on the perforated line 18, the upper portion of this portion 13F being discarded and the lower portion thereof which carries the merchandising establishment's name on the lines 22 is used for attachment to the goods, and as such provides an address label. If for some reason the merchandise cannot be sent at once, the back side of this portion 13F is indicated by the numerals 13G, is sent with the anticipated shipping date of the merchandise and the whole portion 13F which comprises a complete business reply card properly addressed is mailed back to the merchandising establishment originating the special order. It will be observed that the one time carbons 19 and 20 do not extend in under the portion 13F of the form as they terminate slightly above the perforation line 17. This enables the bottom portion of the back cover 11, as indicated by the numeral 11C to be used by the merchandising establishment as a follow-up card on the special order concerned. If the merchandise is not received in the anticipated time this portion of the form is used to make inquiry of the manufacturer or shipper. The back side thereof is indicated by the numeral 11D comprising a standard post card form on which the shipper's name and manufacturer's name will be filled in.

By referring again to the middle section 13D of the form it will be observed that the carbon 21 separates it from the lower portion of the center sheet 14 which is indicated in the drawings by the numerals 14B and this section comprises a duplicate of the form 13D and is retained by the department manager for his record of the special order. The center section of the back portion 11, which is illustrated as being separated somewhat along the perforation lines 16 and 17 and indicated by the numeral 11B which is separated from the portion 14B by a one time carbon 23, is a third copy of the center section 13D of the sheet 13 and as such is detached by the department manager at the time the special order form is filled in and is sent to the order department for their record. The uppermost portion of this back cover, which is also illustrated as being partially separated from the remainder on the perforation lines 15 and 16 and generally indicated by the numeral 11A, is a third copy of the special order originally filled in by the sales person taking the same and is detached by the department manager and placed in the date tickler as heretofore described.

It will thus be seen that a composite special order form has been disclosed which anticipates every requirement of a merchandising establishment with respect to the various forms and orders necessary in making, recording and forwarding the special order to the manufacturer or shipper,

and further that the special order form includes portions which are sent along to the manufacturer or shipper of the goods with the actual order and are detachable by the manufacturer or shipper to become either an address stub for attachment to the merchandise or a business reply card advising of a delayed delivery. The special order form enables two writings on the part of the employees of the merchandising establishment on a single form to establish a complete special order and record of the same, the first person being the sales person taking the order who completes only the top portion of the form such as is indicated by the numeral 13A, the carbons 19 and 20 providing duplicate copies on the portions 11A and 14A of the back cover 11 and center sheet 14, respectively. The middle section is filled in by the department manager and comprises the second and last writing on the part of the merchandising establishment originating the special order. The carbons 21 and 23 provide duplicate copies of this actual order on the portions 14B and 11B of the center sheet 14 and back cover 11, respectively, while the lowermost portion of the special order form provides business reply cards or address stubs for use by the manufacturer or shipper and a business inquiry card for use on the part of the merchandising establishment originating the order.

It will thus be seen that a special order form has been designed which will, in use, expedite the placement of the special merchandise orders on the part of the retail establishment and provides all of the several records necessary for the establishment's complete memorandum of the order, etc.

Having thus described my invention, what I claim is:

1. A special order form comprising a front and back cover having two printed sheets bound therein, the first of the said printed sheets divided into three sections and the second of the said sheets divided by a perforation into two sections, the said two sections matching and underlying two of the sections on the first sheet, perforations on the back cover dividing it into three sections, two of which match and underlie the said two section sheets, carbons interposed between the said sheets, the said first sheet having one of the said sections including a form for entering the customer's order, another section including a form for the department manager's order, and another section including a combined business reply card and address stub, the said second sheet comprising a form for duplicates of the customer's order and the department manager's order, the said back cover having two forms of which correspond with the two sections of the said second sheet and the third section of which comprises a follow-up post card.

2. A special order form comprising a cover having at least two printed sheets positioned therein, the first of the said printed sheets divided into several sections, and the second of the said sheets divided into several sections, at least two of the sections of the said second sheet matching and underlying two of the sections of the said first sheet, the portion of the cover underlying the said printed sheets being divided into several sections at least two of which match and underlie the said printed sheets, carbons interposed between the said printed sheets, the said first sheet having one of the said sections including a form for entering the customer's order, another section including a form for the department mana-

ger's order, and another section including a combined business reply card and address stub, the said second sheet including a form for duplicates of the customer's order and the department manager's order, the said cover underlying the said printed sheets having forms of which correspond with the sections of the said second sheet and an additional section which comprises a follow-up post card.
